CLAIM

The ornamental design for a dispenser head, as shown and described.

DESCRIPTION

FIG. 1 is a front right perspective view of a dispenser head showing our new design.

FIG. 2 is a top plan view of FIG. 1.

FIG. 3 is a bottom plan view of FIG. 1.

FIG. 4 is a right side elevational view of FIG. 1, the left side being a mirror image thereof.

FIG. 5 is a front elevational view of FIG. 1; and,

FIG. 6 is a rear elevational view of FIG. 1.

The broken lines in the drawings depict environmental subject matter only and form no part of the claimed design.
